(57) **CLAIM**

The ornamental design for a chainsaw clutch cover, as shown and described.

DESCRIPTION

FIG. 1 is a top perspective view of a chainsaw clutch cover showing my new design.

FIG. 2 is a bottom perspective view thereof.

FIG. 3 is a front elevational view thereof.

FIG. 4 is a rear elevational view thereof.

FIG. 5 is a top plan view thereof; and,

FIG. 6 is a left side elevational view thereof.

The broken lines in the drawings illustrate portions of the chainsaw clutch cover which form no part of the claimed design.
